(54) **WASHING MACHINE, & DRYING**

(76) Inventor: **Thomas Pearce**

Thomas Pierce Hartwick, Oneida Co. New York Reg.

The schedule referred to in these Letters Patent and making part of the same, containing a description in the words of the inventor Thomas Pierce himself of his Improvement in the machine for washing and drying clothes.

To all to whom these presents shall come Greeting:—
Be it known that I Thomas Pierce of Hartwick in the county of Oneida and State of New York have invented a machine for washing and drying clothes and that the following is a full and exact description of the construction and operation of the said machine as invented by me. It consists of a box 1 foot and 6 inches in depth and 3 feet in length with ends inclined 45 degrees so as to meet at the bottom making the cavity of said box triangular and the width 18 inches. This box is based on 4 legs or standards 11 inches in height on which it stands making the height of the box when a cover one inch in thickness is laid upon it and which is necessary when in use to be 29 inches from the floor on which it stands—From the sides of this box which are perpendicular arises two standards 11 inches in height &c. above the top of the box and exactly half the distance from the ends—Through these standards 2½ inches from the top is a hole for an axle which extends across the machine and is supported by the standards aforesaid which are situated on each side of the box at an equal distance from the ends—This axle being 22 inches in length and either round or square at pleasure is 1½ inch in diameter and constitutes a bearing for a lever which is 6 feet 7 1/4 inches in length and the aforesaid axle passes through this lever at the centre and forms its bearing or fulcrum.

Through this lever which is supported by the horizontal axle aforesaid are two mortises one each side of the axle and commencing 10 inches from the axle and end 22 inches from the axle making the mortise 12 inches in length—Into each of these mortises are put a shaft or arm 2 feet 7 four inches in length extending downwards into the box at an inclination of 45 degrees.

so that by raising one end of the lever the other end is correspondingly and neatly lowered and these arms are fitted with each a foot or perforated board 18 inches in width 1/8th inch in thickness, the holes 3/8 in size and within 1/2 an inch over the whole surface of the foot which foot extends quite across the machine and is exactly similar on each arms the arms are suspended in the said machine by a wooden pin - and 4 or more holes may be made in the arms to take up the length of the same or extend it at pleasure. The manner of operating or using is to seize the lever at either end (which ends are of convenient size for the hands) and alternately raise and lower the end which by raising the foot described or perforated board continually changes the position of the clothes which with hot water and soap are to be put into the triangular box and thus operating a few minutes the clothes are cleansed - The dimensions of the above described machine may be diminished or enlarged as circumstances may require - The arms above mentioned are curved to prevent the water following them over the top of the machine - these may be placed at the bottom of the triangular box on both sides a cleat for the purpose of producing friction by raising the foot as the composition of the clothes increases - In the operation of the machine upon the clothes is not to roll the clothes in the wash but to give a direct conurbation i.e. by first passing them in one direction against the end of the box and again in an exact opposite situation to pass them against the other end and that alternately - The arms are to be curved in order to pass through a smaller place in the box that no water may escape by the friction of the arms - On the right side of the above described box is placed a similar box corresponding in all respects to the one above described, from the sides arises 2 perpendicular standards to the height of 2. feet and these inches above the top of the box these standards run downward into the box on the inside 11 inches quite across the box and on to the standards are fastened by being let into the standards 2. two pieces of board forming girdles on which is laid platform for the support of another box which is made square and only side perforated with holes 3/8 inch and 1/2 inch apart and may be properly termed a vat which is for the reception of the clothes from the sides after cleansing by the wash as above described, the dimensions of this vat or box is 12 inches -

1
inches in length 19 inches in height and 19 inches in width and is situated within the triangular box upon the platform immediately above this square box is a follower for the purpose of compressing the clothes which are put into this vat to that degree that the sides is altogether forced out of the perforated vat which vat admits of removal, the power applied to the follower is simply a lever power obtained by the use of a gearing similar to that which is employed in ordinary jackscrews, 16 by 3 cog wheels working into a stanchion with cog and turned by a common hand crank, at the top of the two standards which extends from the sides of the box into which the platform for the vat are notched above said platform is placed two pieces of boards 22 inches in length and 12 inches in width across, from one to the other standard in order to receive the cog wheel and crank gear and also to direct the course of the stanchion which operates the follower, the mode of operating is to raise the follower by use of a crank and the cog wheel gearing entirely from the vat and put in the clothes while yet wet then apply the power to the follower until a sufficient degree of compressibility causes the escape of the water through the perforations in the vat and the water so excluded falls into the triangular box and is drawn from the same by a faucet at the bottom.

Witnessed,

David Kendall
